UNITED STATES PATENT OFFICE.

CHARLES H. EDGERTON, OF PATON, IOWA.

GEARING.

No. 890,225.

Specification of Letters Patent.

Patented June 9, 1908.

Application filed July 13, 1907. Serial No. 388,612.

To all whom it may concern:

Be it known that I, CHARLES H. EDGERTON, a citizen of the United States, residing at Paton, in the county of Greene and State 5 of Iowa, have invented a certain new and useful Gearing, of which the following is a specification.

The object of my invention is to provide a 10 gearing device for washing machines of the class having agitators to which alternating rotary motion is applied, which gearing device is of simple, durable and inexpensive 15 construction, and which may be operated with a minimum of noise and friction, and which is provided with a balance wheel located 20 between the washing machine body and arranged to be driven at a comparatively high rate of speed to aid in continuing the movement of the agitator after the operator ceases to impart motion to the operating lever.

My invention consists in the construction, arrangement and combination of the various 25 parts of the gearing device, whereby the objects contemplated are attained, as hereinafter more fully set forth, pointed out in my claims, and illustrated in the accompanying drawings, in which,—

Figure 1 shows an enlarged detail sectional 30 view through a portion of the top of the washing machine body illustrating the mechanism for imparting an alternating rotary motion to the agitator shaft by means of a lever to be reciprocated by the operator, 35 and Fig. 2 shows a side elevation of a washing machine provided with a gearing device embodying my invention, a part of the machine body being broken away to show the internal construction.

Referring to the accompanying drawings, 40 I have used the reference numeral 10 to indicate the washing machine body provided with a hinged cover 11. Mounted in the hinged cover is an agitator shaft 12 having an agitator 13 thereon. The parts of the device just described are of the ordinary construction, and form no part of my present invention.

Mounted upon the top of the cover 11 is a 50 casing 13^a surrounding the upper end of the agitator shaft 12, and provided with a horizontal opening designed to receive a slide bar hereinafter described. Within the casing I have fixed to the agitator shaft 12 two pulleys 14 and 15. Fixed to and wound upon

the upper pulley 14 is a flexible strap member 16 extended through an opening in one side of the casing 13^a, and fixed to and wound upon the other pulley 15 is a similar flexible strap member, extended in an opposite direction through the casing 13^a. Slidably mounted in the opening in the casing, is a slide bar 17 having two collars 18 mounted thereon, and adjustably held by means of the set screws 19. Each of these collars is provided with an arm 20, which arm is designed to enter a loop 21 in the flexible strap. Obviously, when these parts are assembled as shown in Fig. 1, and the slide bar 17 reciprocated, an alternating rotary motion will be applied to the agitator shaft. If either of the flexible strap members should become loosened, it may be quickly and easily adjusted by means of the set screws 19, or if it is desired to disconnect either of the strap members from the collars, this may be done by sliding the collars toward the agitator shaft, and then removing the loop of the strap member from the arm on the collar. These flexible strap members may be made of leather 80 or thin steel, or other desirable material.

I provide for imparting a reciprocating motion to the slide bar as follows: Mounted upon one side of the machine body is a lug 22 having an operating lever 23 fulcrumed to it. Pivoted to the upper end of the operating lever is a rod 24 having a downwardly projecting end 25 designed to enter an opening in the adjacent end of the slide bar. In this way a detachable connection is made between the 90 said rod and the slide bar, so that the rod may be detached from the slide bar when the machine cover is elevated.

I provide for operating a balance wheel by means of the operating lever as follows: 95 Mounted upon the bottom of the machine body is a bracket 26 to support a sprocket wheel 27. This sprocket wheel is connected by means of a pitman 28 with the lower end of the operating lever. The balance wheel 100 proper which is indicated by the numeral 29, is supported by means of a bracket 30 fixed to the bottom of the tub, and a small sprocket wheel 31 is mounted on the balance wheel shaft. This sprocket wheel is connected by means of a sprocket chain 32 with the large sprocket wheel 27.

In practical use, and assuming the parts to be assembled as shown, the operator places the articles to be washed, and water within the 110

machine body, and then imparts a reciprocating motion to the operating lever. As before explained, this will impart an alternating rotary motion to the agitators. At the same time, it will impart to the balance wheel a continuous rotary motion at a comparatively high rate of speed, and on account of the agitator shaft and the balance wheel shaft being connected by the devices set forth, the balance wheel will continue to impart to the agitator shaft a rotary motion after the operator has ceased to apply power to the operating lever. If it is desired to open the cover of the machine the operator grasps the rod attached to the operating lever and disconnects it from the slide bar, whereupon the cover may be raised without affecting the operating lever, and when the cover is lowered the rod may be quickly and easily attached to the slide bar. One of the principal advantages I attain in connection with the mechanism described is that the action of the flexible straps on the pulleys will be practically noiseless, and furthermore there will be no danger to the operator on account of the gearing device for operating the agitator shaft, such as is the case in connection with machines of this class where the agitator shaft is operated by a rack and pinion. Another advantage attained by the use of the mechanism beneath the tub is that the lever may be placed on one side of the machine and the balance wheel placed on the opposite side, so that the machinery will be well balanced, and the side of the machine opposite from the operating lever will not be likely to be elevated from the ground, and the machine tilted on account of the motion imparted to the operating lever.

Having thus described my invention, what

I claim and desire to secure by Letters Patent of the United States, therefor, is—

1. In a device of the class described, the combination of an agitator shaft, two flexible strap members fixed to and wound upon the agitator shaft, and extended in opposite directions therefrom, a slide bar having said strap members attached to it, an operating lever, and means for connecting the operating lever with the slide bar. 50

2. In a device of the class described, the combination of an agitator shaft, two flexible strap members fixed to and wound upon the agitator shaft and extended in opposite directions therefrom, a slide bar having said strap members attached to it, an operating lever, and means for connecting the operating lever with the slide bar, said means comprising an arm pivoted to the operating shaft, and the hook thereon detachably connected with the slide bar. 55

3. In a device of the class described, the combination of an agitator shaft, a casing to inclose the upper end thereof, two pulleys fixed to the agitator shaft, a flexible strap fixed to and wound upon each pulley, said straps extended outwardly through the casing in opposite directions, a slide bar mounted in said casing, two collars adjustably mounted on the slide bar and having arms thereon, said straps being detachably connected with said arms, an operating lever, and means for connecting the operating lever with the slide bar. 65 70

Des Moines, Iowa, June 6, 1907.

CHARLES H. EDGERTON.
